POWER RAZOR

William P. Boyd, Nashua, N. H.; Roland B. Burnham, administrator of said William P. Boyd, deceased, assignor of one-half to Gardner W. Pearson, Lowell, Mass., and one-half to Mary P. Boyd, Exeter, N. H.

Application August 11, 1938, Serial No. 224,307

13 Claims. (Cl. 30—43)

This invention relates to power operated safety razors for use in shaving.

I am aware that there are devices in which there is a protecting shield with perforations into which the short hairs enter and inside such a shield some sort of power driven cutting device. I am aware that there are devices in which the shield is of disk shape with perforations through it and in which a cutter either revolves or reciprocates close to the inside flat surface and that there are various types of devices in which the guard is of tubular or semi-tubular form inside of which a cutter or cutting blade revolves or reciprocates.

In all of these devices, however, the cutting blade or member is fixed in position and in many cases, it has a cutting edge which shears along the inside of the guard, cutting the hair by the sharp edge of a blade.

In this device, I use a guard which is a perforated tube fixed to and carried at one end by a housing. A blade holder is revolved inside this tubular guard by a shaft also carried by the housing and driven by power. The power may be provided by an electric motor carried by the housing or in any other way, such as by a flexible power shaft.

This blade holder has one or more longitudinal slots arranged in a plane or planes which may pass through, but preferably a short distance from the axis, so that they rake forward in the direction of rotation.

The blade holder may conveniently be cylindrical and may or may not have a bearing at the free end of the tubular guard.

Instead of a cylindrical blade holder with slots, I can use flat surfaces in planes similar to those just described to one or more of each of which a cutting blade is slidably attached. I so attach the blades by forming slots in them and attaching each by headed screws or pins to a flat surface.

The main principle of my device is the utilization of one or more longitudinal blades which are so carried by a revolvable blade holder that, as they revolve, centrifugal force throws the blades away from the axis and not only causes them to slide along the inside surface of a perforated guard, thus cutting the hair, but preferably, especially if the blades rake forward, automatically sharpening themselves. The raking blades also act as fans to suck in air through the perforations in the guard, although I find it convenient to use fan blades in addition to the cutting blades.

5 Besides cutting the hair, the great advantage of this construction is that each blade will last for a very long time, during which time it does not need to be sharpened. The device, therefore, is always instantly ready for use with no delay for replacing or sharpening blades.

It is preferably used dry and with no lather or shaving cream.

In the drawing, Fig. 1 is a side elevation of a complete power razor of my construction with parts broken away to show the interior construction.

Fig. 2 is an enlarged elevation of the outside of the cap shown in Fig. 1.

Fig. 3 is an enlarged sectional view as from the left of line 3—3 of Fig. 1 but showing also the human flesh and hairs as they appear when the device is operating.

Fig. 4 is an enlarged vertical longitudinal section of the outer end of the device, as shown in Fig. 1.

Fig. 5 is a view similar to Fig. 3 showing a slight modification of the arrangement of a cutting blade and slot.

Fig. 6 is a view similar to Figs. 3 and 5, showing a modification of the blade holder in which there are no slots.

Fig. 7 is a detail sectional view looking in the direction of the arrow on the line 7—7 of Fig. 6.

Fig. 8 is an elevation, with parts broken away and diagrammatic, showing another method of applying power.

Fig. 9 is a vertical longitudinal sectional view similar to the left of Fig. 1, showing a modification of the fan and other details.

Fig. 10 is an elevation of the outside of a modified form of the cap.

In the drawing, H represents a housing on which is an electric switch 11 for starting and stopping an electric motor 12 with a shaft S. 13 represents a flexible cord carrying feed wires 14 and 15 for driving the motor.

45 T represents a tubular guard which is fixed to housing H and which has an interior cylindrical surface 1 and an outside surface 2, there being a flat space 3 on the outside surface. 4, 4 represent a plurality of perforations or hair holes which extend through the wall of the guard. Preferably these are of truncated conical form, being larger at the outside than they are at the inside so that there is at the edge 5 of each, at the interior cylindrical surface 1, a relatively sharp edge.

50 The axis of revolution of the motor 12 and the shaft S carried thereby coincide with the axis

55

of the inside cylindrical surface 1 of guard T. This shaft S carries a blade holder A which may be cylindrical, or of other suitable shape, preferably so made that its parts will properly balance when revolved at a high rate of speed by the motor 12. As shown in Figs. 1 to 3, the blade holder, such as A, is provided with a plurality of longitudinal slots 30 and 31 which rake forward from the axis with reference to the direction of rotation. The sides of these slots, as shown, are parallel and, as shown in Figs. 1 to 3, the planes of their surfaces extended would be parallel with the axis of rotation.

The outer edge, such as 36, of each cutting blade should rake slightly, as shown in Fig. 3, so that its forward edge 37, co-operating with the inner cutting edge 5 of each perforation or hair hole 4 will make a clean cut of each hair of the human beard which projects into each perforation. Whatever shape this edge takes in the beginning, it will gradually wear down so that it will slip along on the inside surface 1 and the cutting edge 37 will always remain sharp.

For convenience in assembling and cleaning, the guard T has interior threads 6 at the end next the motor which engage threads 16 on a hub 18 carried by housing H and interior threads 7 on the outer end which engage exterior threads 47 on a cap C. Cap C, as shown, includes a bearing 48 for the reduced end 8 of holder A and its outside 49 is squared so as to be more readily turned.

As shown, each slot 30 or 31 terminates at 32 or 33 at the housing end and at 34 or 35 at the free end in a dead end. Each slot should be of such a length and width that a blade B can slide with a smooth, running fit and each slot is of such depth that its blade B will be held firmly but slidably. Each blade B is of rectangular form in length and height or depth and may be of substantial thickness, such as one-sixteenth of an inch.

Preferably, the perforations through the tubular guard are of truncated conical form so that the surface or skin of the human flesh K can enter when the hairs, such as L, go through, as shown in Figs. 3 and 5, thus securing a close shave.

To put in place or to remove a blade for any purpose, such as cleaning, the guard T is unscrewed from the threads 16 on hub 18 and, if necessary, the cap C is also removed so that water or other device for cleaning can get at the inside of the guard T.

To take care of the hair which is drawn in through the hair holes 4, 4, I may have air vents or air outlets 17, 17 near the fixed end of guard T or, as shown in Fig. 10, I can use a cap 80 in which there are air vents 81, 81.

As shown in Fig. 9, I can provide a power shaft 20, which may be from an electric or other motor or from a flexible shaft, with a hub 27 to which is screwed one end of tubular guide 21 having hair holes 28 and with no cap at its outer or free end 29.

In this case, the blade holder 22 is provided with blade slots 23 at the inner end of each of which is preferably a recess 24 to receive a tail 124 at one end of a blade, such as 25. The outer end 123 of each slot 23 may be open and there is no bearing at the outer end 129 of blade holder 22, as it is sufficiently held by hub 27.

The open end 29 of the guard 21 takes the place of the air vents and, as shown, I provide the blade holder 22 with fan blades, such as 26, which pitch in such a direction that as they revolve, they help the blades, such as 25, to suck

air in through the hair holes 28 and expel it from the open end 29 of the guard T.

In Fig. 5, I show a blade holder 50 with a single slot 51, the central plane of which extends directly through the axis of the blade holder. There is a single blade 52 in slot 51. This construction is effective but it is more difficult to balance the revolving parts and the faces at the forward edge of the blade 52, being at nearly ninety degrees with the inner surface of the guard, are not as sharp. There is no fan.

In Figs. 6 and 7, I show another modification in which the blade holder 60 is shown as having two parallel flat surfaces 61 and 62, from each of which surfaces project headed pins, such as 63, whereby the two blades 64, 64, each with slots 65, 65 can be held in place by the heads of these pins. As the blade holder 60 revolves at a high rate of speed, centrifugal force throws these blades radially outward so that they run along the cylindrical inside surface of guard 61.

As shown in Fig. 8, in some places, such as barber shops, the driving means carried by a housing 70 can be one end of a flexible shaft 71 which is directly connected to a fixed shaft 12 carrying a blade holder 73 for a blade 74 inside a housing 75.

I claim:

1. The combination in a power shaving device; of a housing carrying driving means and a tubular guard fixed to the housing and having perforations through the wall thereof, said perforations being of truncated conical form and each terminating in a relatively sharp edge at the inside of the guard; with a shaft carried by the housing and revolvable by the driving means; a cylindrical blade holder mounted on said shaft and revolvable inside the guard, said blade holder having a plurality of longitudinal slots arranged in planes which rake forward from the axis towards the direction of rotation; a removable cap carried at the free end of the guard and serving as a bearing for the shaft; and a plurality of cutting blades of rectangular form with a straight outer edge of greater length than the inside radius of the tubular guard and each slidably in a slot in the blade holder.

2. The combination in a power shaving device; of a housing carrying driving means and a tubular guard fixed to the housing and having perforations through the wall thereof, said perforations each terminating in a relatively sharp edge at the inside of the guard; with a shaft carried by the housing and revolvable by the driving means; a cylindrical blade holder mounted on said shaft and revolvable inside the guard, said blade holder having a plurality of longitudinal slots arranged in planes which rake forward from the axis towards the direction of rotation; a removable cap carried at the free end of the guard and serving as a bearing for the shaft; and a plurality of cutting blades of rectangular form with a straight outer edge of greater length than the inside radius of the tubular guard and each slidably outwardly in a slot in the blade holder.

3. The combination in a power shaving device; of a housing carrying driving means and a tubular guard fixed to the housing and having perforations through the wall thereof; with a shaft carried by the housing and revolvable by the driving means; a cylindrical blade holder mounted on said shaft and revolvable inside the guard, said blade holder having a plurality of longitudinal slots arranged in planes which rake forward from the axis towards the direction of rotation; a re-

movable cap carried at the free end of the guard and serving as a bearing for the shaft; and a plurality of cutting blades of rectangular form with a straight outer edge of greater length than the inside radius of the tubular guard and each slidable outwardly in a slot in the blade holder.

4. The combination in a power shaving device; of a housing carrying driving means and a tubular guard fixed to the housing and having perforations through the wall thereof; with a shaft carried by the housing and revolvable by the driving means; a blade holder mounted on said shaft and revolvable inside the guard, said blade holder having a plurality of longitudinal slots arranged in planes which rake forward from the axis towards the direction of rotation; and a plurality of cutting blades of rectangular form with a straight outer edge of greater length than the inside radius of the tubular guard and each slidable outwardly in a slot in the blade holder.

5. The combination in a power shaving device; of a housing carrying driving means and a tubular guard fixed to the housing and having tapered hair holes and an air vent through the wall thereof; with a shaft carried by the housing and revolvable by the driving means; a blade holder mounted on said shaft and revolvable inside the guard, said blade holder having a longitudinal plane surface extending in a substantially radial direction and a fan blade proximate the air vent; and a cutting blade of greater length than the inside radius of the tubular guard and slidable outwardly on such plane surface so as to engage the inner surface of the tubular guard.

6. The combination in a power shaving device; of a housing carrying driving means and a tubular guard fixed to the housing and having hair holes and an air vent; with a shaft carried by the housing and revolvable by the driving means; a blade holder mounted on said shaft and revolvable inside the guard, said blade holder having a longitudinal plane surface extending in a substantially radial direction and a fan blade; and a cutting blade of greater length than the inside radius of the tubular guard and slidable outwardly on such plane surface so as to engage the inner surface of the tubular guard.

7. The combination in a power shaving device; of a housing carrying driving means and a tubular guard fixed to the housing and having perforations through its wall; with a blade holder revolvable inside the guard by the driving means, said blade holder having a longitudinal slot of greater length than the inside radius of the tubular guard and which extends in a substantially radial direction outward from proximate the axis of rotation; and a cutting blade slidable outwardly in said slot.

8. The combination in a power shaving device; of a housing carrying driving means and a tubular guard fixed to the housing and having perforations extending entirely around and through its wall; with a blade holder revolvable inside the guard by the driving means, said blade holder having a flat longitudinal guiding surface which

extends in a substantially radial direction outward from proximate the axis of rotation; and a cutting blade with a straight outer edge of greater length than the inside radius of the tubular guard and slidable outwardly along said guiding surface.

5 9. The combination in a power shaving device; of a housing and of a guard fixed to the housing and having a cylindrical interior and perforations through its wall; with a blade holder revolvable inside the guard, said blade holder having a flat longitudinal guiding surface which extends in a substantially radial direction outward from proximate the axis of rotation; a cutting blade with a straight outer edge of greater length than the inside radius of the tubular guard and slidable outwardly along said guiding surface; and driving means for the blade holder carried by the housing, said driving means being sufficient to overcome friction and to throw the cutting blade out by centrifugal force.

10 10. The combination in a power shaving device; of a housing carrying driving means and a tubular guard fixed to the housing and having perforations through its wall; with a blade holder attached to and revolvable by the driving means and having a longitudinal slot with parallel side walls which extend longitudinally of the axis of the guard in a substantially radial direction outward from proximate said axis which is the axis of rotation; and a cutting blade with parallel side walls, which blade fits the slot with a smooth, running fit, the blade being of greater length than the inside radius of the tubular guard and being slidable outwardly in said slot.

15 11. The combination in a power shaving device; of a housing carrying driving means and a tubular guard fixed to the housing and having perforations through its wall; with a blade holder attached to and revolvable by the driving means and having a flat longitudinal guiding surface which extends in a substantially radial direction outward from proximate the axis of the guard which is the axis of rotation; and a cutting blade with a straight outer edge which is parallel with said axis and is of greater length than the inside radius of the tubular guard, the blade being closely slidable outwardly along said guiding surface.

20 12. A rotary razor including a motor, a shaft extending from said motor, an enlarged extension on said shaft, longitudinally extending radial slots in said extension, razor blades loosely mounted in said slots, a fan-blade secured to the said shaft between the enlarged extension and the motor, and a tubular housing surrounding said shafts, razor blades and fan-blade.

25 13. In a rotary razor, a handle, a motor within the handle, a shaft extending from the motor, approximately radial slots in said shaft, blades slidable positioned within said slots, and a perforated tubular housing adapted to cover said shaft and blades, said tubular housing having a closed end provided with a bearing for supporting the end of the motor shaft.
